G. F. FINZER

CLOTHES BOILER ATTACHMENT

Filed March 10, 1924

Inventor:
George F. Finzer,

Attorney

By H. L. Woodward,

Patented Apr. 20, 1926.

1,581,996

UNITED STATES PATENT OFFICE.

GEORGE F. FINZER, OF HICKSVILLE, OHIO.

CLOTHES-BOILER ATTACHMENT.

Application filed March 10, 1924. Serial No. 698,174.

To all whom it may concern:

Be it known that GEORGE F. FINZER, a citizen of the United States, residing at Hicksville, in the county of Defiance and

5 State of Ohio, has invented certain new and useful Improvements in Clothes-Boiler Attachments, of which the following is a specification.

The invention has for an object to effect 10 improvement in means for handling the domestic wash or home laundry work, and particularly in facilitating the conduct of the operation of boiling clothes in the familiar "wash boiler." In the cleansing 15 of garments and other fabrics, it has been determined by long usage that boiling the pieces for a period in water suitably saponified, and possibly otherwise modified, enables the removal of dirt with much less agitation or rubbing than otherwise, and consequently reduces the wear of the fabrics in 20 the laundering process which is often a serious factor. In domestic practice of this method the fabrics are introduced into a 25 suitable quantity of water in a "wash boiler" which is set upon a stove or other heater and the contents boiled for a period. These boilers are of a limited size, adapted to domestic stoves. One woman ordinarily performs the labor on the domestic wash.

In removing the clothes it is customary 30 (on account of the boiler and contents being too heavy to be moved bodily, and often also to conserve heat by introducing a second 35 and even a third batch into the same water) to remove the fabrics without moving the boiler and water therein, and in this there is much risk of spilling water, scalding the person, and of other accidents. It is therefore 40 an important aim of my invention to improve the means for transferring fabrics from a wash boiler while resting upon a stove to the end of lessening the spilling of water, injury, and soiling of fabrics, and 45 liability of accident generally.

It is a further important object to improve specific structure of elements in such devices, as will be readily understood, the invention also residing in part in the combination and arrangement of parts, all of 50 which will be more readily understood from the following description and accompanying drawings, in which—

55 Figure 1 is a perspective view of a boiler and transfer device embodying my invention.

Figure 2 is a similar view of the transfer device alone.

Figure 3 is a top view of the transfer 60 device.

Figure 4 is a side elevation thereof.

Figure 5 is a fragmentary perspective view of the swinging end of the grid.

There is illustrated a wash-boiler 10 of conventional form, with which there is 65 operatively associated a transfer device 11, in the form of a bucket-like receptacle. It has a flattened and nearly or quite vertical side 12, and is also of the same height as the boiler 10, so that it may be set thereagainst 70 with its flat side forming a snug fit with the side of the boiler at the upper part. From the side 12 at its upper edge there is extended a pouring lip 13 curved downward in such manner as to engage within the 75 boiler 10 and retain the two receptacles against casual separation as long as they are set upon surfaces in the same plane. The curve of—and space under—the lip, are such that the transfer device may be pivoted 80 on the edge of the boiler when the bottom of the transfer device is lifted and swung outwardly for pouring water from this receptacle into the boiler (this involves a loose fit of the boiler edge under the lip). The 85 extremity of the lip engages the inner surface of the boiler, and the body of the transfer device slides slightly upon the edge of the boiler in such operation. The sides of the transfer device and of the lip portion 90 may be raised if desired sufficiently to prevent water from spilling over the sides when being poured as indicated.

The receptacle 11 is provided with a bail 95 14 of heavy wire having a handle 15 and pivoted in a familiar way in apertured ears 16 secured to the sides of the receptacle and extending above its upper edge a distance. The eyes 17 at the ends of the bail engaged in the ears 16, and by which the bail is 100 pivoted, are formed preferably by bending the wire outwardly at the beginning of the eye and then curving the extremity inward to complete the eye, so that the end is not exposed at the outer side. This has an important functional value, as will be explained.

Hinge leaves 19 are provided upon the receptacle at its upper edge adjacent one of the ears 16, and if desired may be formed 110 as a unit therewith. Upon these there are hinged respective bars 21 of a grid 20, nor-

mally extending across the top of the receptacle 11 and resting upon its opposite edge portion. These bars are so spaced that with the handle 15 in raised position they may 5 be swung upwardly beside the bail and handle, then outwardly and downwardly to lie beside the receptacle 11 in inoperative position. They are connected at their swinging ends by an integral cross portion 10 22 turned downward at right angles and continued across the ends of the bars, its upper edge between the bars and its lower edge being rolled outwardly, as indicated at 23 and 24 respectively. The portion 22 is 15 located so as to lie close to the outer side of the ears 16 when in operative position, and this results in the eye of the bail serving as a latch to hold the grid in place, but readily movable by moderate pressure upwardly when the bail is raised. In movement to operative position across the receptacle 11 the portion 22 rides upon the bail wire and wards the eye of the bail inwardly as it engages thereupon, a slightly increased pressure being sufficient to cause it 25 to snap under the eye.

Then, when the bail is lowered as indicated in Figure 3, the grid is positively retained in place so that it will withstand the 30 pressure of fabrics within the receptacle 11 when the water is being poured therefrom, as will be explained. The bar 21 next the side 12 may be provided with a series of integral tines 25 adapted to extend into proximity with the lip 13, and it is discretionary whether the other bar is similarly formed or the tines omitted from both. A bottom grip 26 may also be provided on the receptacle 11 at its outer side to facilitate its tilting for 40 pouring of water, if desired.

In use of the appliance, a clothes boiler being upon a stove with fabric contents ready for removal, the boiler being uncovered, my transfer device is set there- 45 beside with the lip 13 engaged over the edge of the boiler as shown, the grid 20 being in inoperative position. The fabrics are then lifted from the boiler into the receptacle 11 with tongs or other means, 50 and when the water content of the receptacle 11 becomes excessive, the bail is raised and the grid 20 swung down to place across the top of the receptacle 11, after which the grip and bail are grasped and the receptacle 11 tilted 55 toward the boiler, the lip 13 serving as a ful-

crum, until the water is poured back into the boiler. The receptacle 11 may be then raised by the bail 14 and carried to a place for other disposal of the fabrics therein, or may be returned to position to receive further 60 fabrics and the removal and drainage of fabrics repeated as described, before removal of the receptacle 11. In this way the bulky 65 contents of a wash boiler may be removed in easy stages suited to the strength of a frail person, enhancing the safety of the work, and minimizing the liability of soiling or injuring delicate fabrics.

It will be seen that the appliance is adapted to be produced in accordance with familiar 70 practice in making sheet metal ware, and is inexpensive, light in weight and adapted to function in a satisfactory way for the the ends in view. Various modifications of structure may be found desirable within the 75 scope of the claims.

I claim:

1. A transfer device for the purpose described comprising a transfer receptacle adapted for extensive abutting contact with 80 other receptacles, means to hold the transfer receptacle in such relation to another receptacle removably, a grid pivoted on one side of the receptacle, movable to and from operative relation across the top of the transfer 85 receptacle, and means to releasably hold the grid in operative position.

2. The device of claim 1 in which the last named means includes a bail on the transfer receptacle, a transverse element on the grid 90 and an eye on the bail having a rounded part disposed in the path of said transverse element of the grid.

3. The device of claim 1 in which the grid includes a plurality of bars hingedly mounted at one side of the receptacle adjacent the pivot of the bail, two of said bars movable to receive the bail therebetween, and a transverse connection between the outer ends of the bars adapted to swing close beside the side of the receptacle opposite the hinged mounting of the grid, the bail including an inclined part extending outwardly of the said transverse connection to be engaged and warded inwardly thereby under upward and downward movement of the grid, the bail being movable downwardly to lie closely over the grid.

In testimony whereof I affix my signature.
GEORGE F. FINZER.
